COMBINED FURNITURE PEDESTAL AND ADJUSTABLE CASTER UNIT

Wayne W. Good, Sturgis, Mich., assignor to Harter
Corporation, Sturgis, Mich., a corporation of Michigan

Filed May 20, 1965, Ser. No. 85,376

Term of patent 14 years

(Cl. D33—1)

FIG. 1 is a side elevational view of the combined furniture pedestal and adjustable caster unit, showing my new design.

FIG. 2 is an elevational view taken from the front.

FIG. 3 is an elevational view taken from the rear.

FIG. 4 is a fragmentary side elevational view showing the caster in extended position; and,

FIG. 5 is a top view partly in cross-section taken at the line 5—5 of FIG. 4.

The dominant features of my design are shown in full lines and reside in the combination of a pedestal of rectilinear appearance and a cowled adjustable caster unit which boxes in the pedestal and which cowl has a rectilinear appearance on three sides, including the side opposite the caster supports, said caster supports being integral with

and extending from the said cowled caster unit and presenting an angled substantially rectilinear appearance when viewed from the side, all as shown.

I claim:

The ornamental design for a combined furniture pedestal and adjustable caster unit, substantially as shown and described.
